Thurston & Baker.

UNITED STATES PATENT OFFICE.

FRANK S. INGOLDSBY, OF ST. LOUIS, MISSOURI.

DUMP-CAR.

SPECIFICATION forming part of Letters Patent No. 706,662, dated August 12, 1902.

Application filed December 13, 1900. Serial No. 39,664. (No model.)

To all whom it may concern:

Be it known that I, FRANK S. INGOLDSBY, a citizen of the United States, residing at St. Louis, in the State of Missouri, have invented 5 a certain new and useful Improvement in Dump-Cars, (Case A,) of which the following is a full, clear, and exact description, reference being had to the accompanying drawings.

10 My invention relates to dump-cars, comprising dumping railway-cars, wagons, or other vehicles, of the general type shown in my prior United States patents, Nos. 551,319, 613,279, 632,650, granted, respectively, De- 15 cember 10, 1895, November 1, 1898, September 5, 1899. In these patents there appears a dumping vehicle having sides and a central longitudinal beam and dumping-doors hinged to the beam and engaging at their edges with 20 the sides and adapted to swing downward to dump the load, and in order to make a tight joint there exists at each edge of the door an outward bevel, and corresponding bevels are formed on the coöperating parts, and means 25 are provided for drawing the doors snugly into place.

Now the above-mentioned construction I have found from practice works admirably; but it has two occasional disadvantages, which 30 it is the object of the present invention to overcome. These disadvantages are, first, that in use the car-floor if not thoroughly seasoned may shrink away from the edge of the car, so that the bevel edge will not fit 35 tightly, wherefore if the load carried is of a fine character a material part of it may leak out through such crack. To overcome that difficulty, I have heretofore when the crack occurred simply secured to the edge of the floor 40 an additional filling-strip. I have discovered, however, that by rabbeting the edge of the floor, so that it will extend horizontally for some distance beneath the coöperating part of the car, such filling-strip is rendered un- 45 necessary, as when the door shrinks though the bevel may not contact the horizontal rabbet will, wherefore whatever material starts to leak through the crack will simply lodge on the ledge provided by the horizontal por- 50 tion. This is one feature of the present in-

vention. The other difficulty which I have found sometimes attends my dumping-vehicles as heretofore constructed is that when the dumping-floor is lowered only part way to discharge the load to the outside of the 55 track instead of vertically downward and the material is of a sticky character some of it sometimes is lodged in the groove comprised between the bevel at the lower edge of the central beam and the bevel at the inner edge 60 of the door and has to be scraped out before the door can be closed.

The present invention obviates the last-mentioned difficulty by making a curve at the edge of the central beam instead of a straight 65 bevel and pivoting the door at the center of this curve, the door carrying a coöperating curve substantially contacting with the curve carried by the central beam, so that whatever the position of the door substantially a snug 70 contact is maintained between it and the central beam. In accomplishing this I place the pivot of the door substantially at the lower corner of a triangular-shaped central beam. This has in itself an advantage over my prior 75 method of pivoting the door below the edge of the beam, for by raising this pivot a wider door may be used without raising the car. As one of the limiting factors in the construc- 80 tion of efficient dump-cars is the requirement that the center of gravity be kept low and as the door in order to swing to a vertical position cannot be wider than the distance of its pivot above the road-bed, it will be seen that by raising the location of the pivot of the 85 door without raising the center of the gravity of the car the door may be made wider, and hence the capacity of the car increased. These features of the location of the pivot and the continuously-engaging edges of the 90 car-doors and central beam are also important parts of the present invention.

In the drawings, Figure 1 is a side elevation of a dump-car, various parts not contributing to the present invention being removed. 95 Fig. 2 is an enlarged vertical transverse section thereof. Fig. 3 is a still more enlarged transverse section of the hinge of the dumping-door. Fig. 4 is a plan of the dumping-door, being on the same scale as Fig. 2. 100

Referring to the parts by letters, A represents the side of the vehicle, B the longitudinal central beam, and C the trap-doors hinged thereto. Each of the three free edges of these trap-doors are preferably beveled, as at c' , to make the tightest possible joint when the doors fit snugly; but this bevel is interrupted by the offset or rabbet c^2 . The purpose of this rabbet is to provide a horizontal surface which engages with the horizontal surface on the under side of that part of the car with which the free edges of the door contact. Now the door being drawn up against the car a tight joint is made at these coöperating horizontal surfaces, and even if the bevels do shrink away no material can leak, for what starts to pass between the floor and car is interrupted by the horizontal rabbet.

The door is drawn snugly into place by the hooks D, carried by the side of the car and engaging with projecting straps E, secured to the under side of the doors, the ends of the hooks being beveled to draw the door snugly against the car. As shown, the hooks are conveniently operated by the lever F, connected therewith by a link G.

At their inner ends e the door-straps E turn upward, coming at the rear end of the flooring of the door, and secured to the under side of the central beam is the hinge-strap H, which has its ends h correspondingly turned upward, and joining these upturned ends substantially at the theoretical corner of the central beam are hinge-pintles J. The beam and floor are of course so formed as to accommodate this position of the hinge members, and in addition the central beam is curved concavely on a center coincident with that of the hinge-pintles, as shown at b , and a convex surface c^3 is carried by the floor above the hinge-pintles and substantially engaging with the concave surface.

In the form shown in the drawings, where the floor is composed of planking, the convex surface referred to is a shield c^4 , bolted or screwed to the wooden planking and extending across the hinge-joint in a curve concentric with the curve b and of sufficient length so as to substantially engage with that concave curve whatever the position of the door.

Now when the door is in locked position, as shown in Fig. 2 and as shown in dotted lines in Fig. 3, no material can escape at the central beam, for the joint is tight, while when the door is dropped to release the load—say to a forty-five-degree position, as shown in Fig. 3—the joint is still tight and there is no crack which may become filled with material and require its removal, the load simply sliding down over the shield and flooring. The convex surface which the floor carries to make this engagement with the central beam continues across the end of the rabbeted edge of the door, as shown in Fig. 4, so that there is no chance for any material to leak at the cor-

ner if the flooring should shrink. Thus with the improvements shown herein the doors will close tightly, preventing the load from leakage at any point, even though the floor should shrink in practice, and without requiring any additional filling-strips, while when the load is dumped it is provided with a substantially continuous surface on which it may slide out of the car and there is no groove or ledge on which it may lodge.

Having described my invention, I claim—

1. In a dump-car, in combination, a dumping-door which swings downward, and a car side with which said door is adapted to substantially engage, the coöperating edges of said door and side being beveled and rabbeted, and means for forcing the door and side snugly together whereby the bevels may normally engage forming a tight joint and if the door shrinks the horizontal face of the rabbet may still engage preventing leakage, substantially as described.

2. In a dump-car, in combination, a beam having a recess at its lower edge, a dumping-door pivoted to said beam by hinges which occupy said recess, and a shield carried by the door and adapted to extend into the recess over the hinge in various positions of the door, substantially as described.

3. In a dump-car, the combination of a beam having a downwardly-sloping upper surface, said beam being recessed along its lower edge, a dumping-door pivoted to said beam substantially within such recess, and a metal shield carried by said door and extending over the hinges, said shield curving over the hinged pivot when the door is dumped and operating to substantially close the entrance to such recess in various positions of the door, substantially as described.

4. In a dump-car, in combination, a beam downwardly sloping in opposite directions on its upper surface, the lower edges of said beam being recessed, a strap extending across the under side of said beam and provided at its ends with hinge-eyes substantially at said recesses, a pair of dumping-doors having straps on their under surface, hinge-pintles connecting the beam-straps with the door-straps, and shields carried by the doors and extending over the hinges into said recess, substantially as described.

5. In a dump-car, a central longitudinal beam having its lower edges formed in concave curves, combined with a pair of dumping-doors hinged to said central beam on pivots substantially concentric with such curves, and a shield carried by the upper surface of said doors and extending across the pivots thereof, said shield being curved so as to substantially contact with said concave edge in all positions of said doors, substantially as described.

6. In a dump-car, a beam having a concavely-curved edge, and a dumping-door

hinged to said beam on pivots substantially concentric with such curve, the hinge members being spaced along the under sides of the beam and door and secured respectively thereto, and a shield carried by the upper surface of the door and extending along the inner edge thereof and curved over the hinge-pinnacles and confined between the curve of the

beam and the ends of the hinge members secured to the door, substantially as described. ¹⁰

In testimony whereof I hereunto affix my signature in the presence of two witnesses.

FRANK S. INGOLDSBY.
